UNITED STATES PATENT OFFICE.

STEVE MISCO, OF GARY, WEST VIRGINIA.

DETACHABLE SHOE-SOLE.

1,367,919.

Specification of Letters Patent.

Patented Feb. 8, 1921.

Application filed July 10, 1919. Serial No. 309,838.

To all whom it may concern:

Be it known that I, STEVE Misco, a citizen of the United States, residing at Gary, in the county of McDowell and State of West 5 Virginia, have invented certain new and useful Improvements in Detachable Shoe-Soles, of which the following is a specification.

This invention relates in general to shoes 10 and more particular to half-soles or soles therefor.

One object of this invention is the production of means whereby when a sole is provided with these means it may be easily applied and retained in position on an old or worn sole.

Another object of this invention is the production of a shoe sole wherein a plurality of hooks are mounted upon the sole to be 20 easily applied over the periphery of the original sole of a shoe, a number of the hooks being movably mounted and actuated by a latch lever so that they may be finally clamped in position and thus hold the sole 25 against displacement.

One practical form of construction and assembly of the present invention will be hereinafter described and is illustrated in the drawings, wherein:—

30 Figure 1 is a side elevation of the shoe sole applied to the sole of a shoe.

Fig. 2 is a top plan view of the invention.

Fig. 3 is an enlarged fragmentary section taken on the line 3—3 of Fig. 2.

35 Fig. 4 is an enlarged transverse fragmentary sectional view of the device taken on the line 4—4 of Fig. 2.

In the preferred embodiment of the present invention, about to be specifically described, 5 indicates the shoe sole, the construction of which is clearly illustrated in Fig. 2. This sole is of conventional shape although of course, it may be of various sizes in order to fit neatly upon shoe soles of various sizes and shapes.

45 Adjacent the periphery of the sole 5 are carried a plurality of studs 6. The hooks 7 have elongated bodies 8 provided with eyes 9 at their inner ends. The studs 6 pass through the eyes 9 and thus fixedly although pivotally support the hooks 7 contiguous to the periphery of the sole as illustrated in Figs. 2 and 4. In order to hold the body 7 from swinging too far to either side, retaining yokes 10 are positioned thereover and

have their ends carried within the shoe sole 5 as shown in Figs. 2 and 4 thereby allowing the hooks 7 to be swung slightly from side to side as the sole is being placed upon the old sole of a shoe, as the conditions may require. 60

A plurality of hooks 7' have bodies 8' upon the inner ends of which are formed rectangular loops 11, as shown in Fig. 3. These loops are formed by looping the inner ends of the bodies 8', the loops extending in the 65 same direction as the bodies 8' as shown in Figs. 2 and 3. Retaining yokes 10 are positioned over the bodies 8' in a manner similar to which the yokes are placed over bodies 8, thus guiding the outer end of the 70 bodies.

A latch lever 12 has an eye 13 at its inner end carried pivotally upon a stud 14 secured to the sole 5. This latch lever 12 is offset as shown at 15 intermediate its ends, 75 it being noted that the lever passes through the loops 11 of the hooks 7'. The manner of offset allows one hook to move a greater distance than the remaining hook as shown in Fig. 2 in dotted lines. This lever has a 80 handle portion 16 at its free end which is adapted to engage a keeper 17 carried by the sole 5. It will be noted that the handle portion 16 is of a hook-like construction and projects beyond the inner end of the sole 5 85 so that access may be had thereto for swinging the lever as a sole is being applied to the old original sole of a shoe.

By referring to Fig. 1 it will be noted that a conventional form of shoe is shown at 18 90 and this shoe is provided with an original sole 19.

As is well known, when the shoe sole is worn considerably until it is very thin or until a hole has been worn therethrough it is 95 the general practice to repair the same by having a shoe "half-soled" or "whole soled," these half and whole soles being retained in position on the original sole by either tacking or stitching the same thereto. 100 This is an expensive operation and also generally causes a great deal of inconvenience in the time consumed in such operation.

By employing the present device, the supplemental sole may be applied in a few 105 seconds. Obviously such soles may be carried in stock in various stores and may be sold to purchasers just as various shoe attachments are now disposed of. Under such circumstances, the purchasers could select a sole 110

which would conform to the shape and size of the shoe to be repaired. In order to apply the supplemental sole, all that would be necessary to do would be to swing the lever toward the outer edge of the sole 5 as shown in dotted lines in Fig. 2. The sole 19 of the shoe 18 could then be slipped onto the sole 5 so that the hooks 7 would be slipped over the outer edge of the sole 19 as shown in Fig. 1. 10 In order to prevent displacement of the sole 5, the user could then pull inwardly upon the projecting end of the handle 16, it being noted that this handle extends beyond the inner end of the sole 5 as shown in Figs. 1 15 and 2. A swinging of the lever would cause the hooks 7' to be retracted from the position indicated in dotted lines in Fig. 2 to the position indicated in full lines therein whereby these hooks 7' would also engage 20 over the edge of the sole 19 of the shoe 18. As the space between the rear hooks is constricted considerably, obviously the sole 5 could not pull from the sole 19. When the lever is swung inwardly a sufficient distance 25 it will engage behind the keeper 16 and will thus be held in a set position so that the supplemental sole 5 will be fixed upon the sole 19. Therefore it will be seen that the device 30 may be operated so that the supplemental sole may be quickly and easily placed on the original or old worn sole to constitute a new sole therefor without necessitating the stitching or tacking of the supplemental sole in position. Neither does the device require an experienced person to attach the same in position for it is simply necessary to slip the new sole onto the old sole at which time the hooks 7 will engage as above specified and then by swinging the lever until it is retained by the keeper 16 the hooks 7' actuated 35 thereby will also engage the sole 19 whereby the supplemental or new sole will be fixed in position for use.

The foregoing description and accompanying drawings have reference to what might be considered to be the approved or preferred form of my invention. I desire it to be understood that I may make such changes in the construction, combination and arrangement of parts, materials, dimensions, et cetera, as may prove expedient and fall within the scope of the appended claims.

Having thus fully described my invention what I claim as new and desire to secure by 55 Letters Patent, is:—

1. In a device of the character described, the combination of a shoe sole, hooks having elongated bodies terminating in eyes at their inner ends, studs passing through said eyes for fixing said bodies upon said soles adjacent the edge thereof, yokes positioned over said bodies for allowing the same to swing slightly although holding the hooks adjacent the edge of said sole, and clamping means carried by said sole operative in conjunction with said hooks. 60

2. In a device of the character described, the combination of a shoe sole, of attaching means thereof including hooks fixed upon the sole adjacent the periphery thereof, a latch lever pivotally mounted upon said sole and having a handle portion at its free end, a keeper in the path of movement of the said handle portion and carried by said sole, other hooks having bodies provided with loops at their inner ends, said lever passing through said loops whereby as the lever is swung said hooks may be moved to a retracted position, at which time said keeper will engage the handle portion to hold the lever 75 in a set position.

3. In a device of the character described, in combination, a shoe sole, a plurality of laterally adjustable attaching hooks fixed to the sole adjacent the edge thereof, other hooks slideable upon one side of the sole adjacent the rear edge thereof, a latch lever pivoted to the sole at one end and connected to said slideable hook at points inwardly of its fulcrum and handle end, whereby actuation of the lever moves the last mentioned hooks for enlarging or constricting the space between the rearmost attaching hooks of the sole. 85

4. In a device of the character described, in combination, a shoe sole, a plurality of attaching hooks adjustably fixed to the sole adjacent the edges, and a latch lever pivoted to the sole and having relatively offset portions engaging certain of said hooks for projecting them to unequal distances beyond the edge to facilitate the attachment of the sole to a shoe or other object. 90

In testimony whereof I affix my signature in presence of two witnesses.

STEVE MISCO.
